UNITED STATES PATENT OFFICE.

NICHOLAS J. YONKER, OF HOLLAND, MICHIGAN.

HUMIDIFYING APPARATUS.

1,211,905.

Specification of Letters Patent.

Patented Jan. 9, 1917.

Application filed October 25, 1916. Serial No. 127,512.

To all whom it may concern:

Be it known that I, NICHOLAS J. YONKER, a citizen of the United States, residing at Holland, in the county of Ottawa and State 5 of Michigan, have invented new and useful Improvements in Humidifying Apparatus, of which the following is a specification.

The present invention relates to humidifying apparatus, and its object is generally 10 to provide apparatus of that character which shall be simple and economical in construction; and more particularly, an apparatus of that character wherein the water which is being vaporized may be maintained 15 at a desired level, and may be replenished from heated water under pressure; and further, to provide improved means for regulating the heating of the water. This, and any other objects appearing hereinafter, are 20 attained by, and the invention finds preferable embodiment in, the illustrative structure hereinafter described and illustrated by the accompanying drawings, in which:—

Figure 1 is a sectional view of a humidifying apparatus taken on a vertical plane corresponding to line A—B of Fig. 2, and showing a hot-air furnace as the heater of such apparatus; Fig. 2 is a top plan view of the same; Fig. 3 is a sectional view 30 of the same taken on vertical planes corresponding to line C—D of Fig. 2; Fig. 4 is a detail view of a float-operated valve, partly in axial section; and, Fig. 5 is a view of a screen for shutting off heat from the water 35 containers of the humidifying apparatus.

In the embodiment of the invention chosen for illustration by the drawings and for detailed description in the body of this specification, the apparatus is employed for 40 humidifying air in dwellings and the like. An ordinary "hot-air" furnace 1, having the casing 2 and placed preferably in the basement, for heating the air, is also utilized for evaporating the water for humidifying 45 the air.

The apparatus is located within the air-heating chamber formed by the casing, and comprises a closed water container 3, into 50 which water is forced through a pipe 4 by suitable means, as from an elevated head or by the water pressure exerted by the pumping system from which said pipe leads. Under such pressure, the water passes from the closed container into an open evaporating water container 5 through a suitable inlet 6 controlled by automatic means, as the

float-operated valve 7 of common form and having the ball float 8. It will be seen that when the water in the open container is exhausted by vaporization to a certain level, 60 the valve automatically opens, and replenishing water passes into the open container, being forced thereinto by the pumping system or the water head pressing on the water in the closed container; and that when the 65 incoming water reaches the desired level, the valve closes. It will be seen also, that the water while in the closed container is being heated and thus prepared for ready vaporization, but by reason of being confined under pressure, can not boil at the same temperature as that in the open container. It will be also seen that the water in the open or evaporating container is maintained at a certain level by the water 75 head, or pumping system as automatically controlled by the valve, and hence said container cannot become exhausted and dry. A suitable screen or shield 9 is movable 80 into and out of positions between the heater and one or both of the containers, whereby the heat may be to a greater or less degree shut off from one or both containers, as may be desired. As shown, this screen is slideable in ways 10 and may be raised or lowered by 85 a cord 11 attached thereto and passing over pulleys 12, 13. The container 5 is shown provided with a corrugated inner wall 14 whereby the heating of the water therein is facilitated.

The invention being intended to be defined solely by the claims, is not to be limited to or by details of construction shown or described.

I claim:

1. In apparatus of the character described; a closed water container; means for forcing water thereto; an open water container, having an inlet thereto whereby water may flow from the closed to the open container; means for automatically controlling said flow; and a heater for heating the water in the containers and vaporizing the water in the open container.

2. In apparatus of the character described; a closed water container; means for forcing water thereto; an open water container, having an inlet thereto whereby water may flow from the closed to the open container; a float-operated valve in the open 100 container for automatically controlling said flow; and a heater for heating the water

in the containers and vaporizing the water in the open container.

3. In apparatus of the character described; a closed water container; means for forcing water thereinto; an open water container, having an inlet thereto whereby water may flow from the closed to the open container; a float-operated valve in the open container for automatically controlling said flow; a heater for heating the water in the containers and vaporizing the water in the open container; and a screen adapted to be moved into and out of position between the heater and said container.

4. In apparatus of the character described; a closed water container; means for forcing water thereinto; an open water container, having an inlet thereto whereby water may flow from the closed to the open container; a float-operated valve in the open container for automatically controlling said flow; a heater for heating the water in the containers and vaporizing the water in the open container; and a slidably mounted screen adapted to be slid into and out of position between the heater and said container.

5. In apparatus of the character described; a closed water container; means for forcing water thereinto; an open water container, having an inlet thereto whereby water may flow from the closed to the open container; means for automatically controlling said flow; a heater for heating the water in the containers and vaporizing the water in the open container; and a casing for the containers and the heater.

6. In apparatus of the character described; a closed water container; means for forcing water thereinto; an open water container, having an inlet thereto whereby water may flow from the closed to the open

container; a float-operated valve in the open container for automatically controlling said flow; a heater for heating the water in the containers and vaporizing the water in the open container; and a casing for the container and the heater.

7. In apparatus of the character described; a closed water container; means for forcing water thereinto; an open water container, having an inlet thereto whereby water may flow from the closed to the open container; a float-operated valve in the open container for automatically controlling said flow; a heater for heating the water in the containers and vaporizing the water in the open container; a screen adapted to be moved into and out of position between the heater and said container; and a casing for the container and the heater.

8. In apparatus of the character described; a closed water container; means for forcing water thereinto; an open water container, having an inlet thereto whereby water may flow from the closed to the open container; a float-operated valve in the open container for automatically controlling said flow; a heater for heating the water in the containers and vaporizing the water in the open container; a slidably mounted screen adapted to be slid into and out of position between the heater and said container; and a casing for the containers and the heater.

In testimony whereof I have hereunto set my hand in presence of two subscribing witnesses, at Grand Rapids, Michigan, this 19th day of October A. D. 1916.

NICHOLAS J. YONKER.
